UNITED STATES PATENT OFFICE.

THOMAS J. WAVRUNEK, OF SHAWANO, WISCONSIN.

COMPUTING MACHINE.

Application filed September 18, 1920. Serial No. 411,256.

To all whom it may concern:

Be it known that I, THOMAS J. WAVRUNEK, a citizen of the United States, residing at Shawano, in the county of 5 Shawano and State of Wisconsin, have invented certain new and useful Improvements in Computing Machines, of which the following is a specification, reference being had to the accompanying drawing, forming 10 a part thereof.

This invention relates more particularly to computing machines having number bearing wheels and means for rotating them determinate variable degrees to indicate 15 numbers, perform the operations of addition and subtraction, and register the results.

Its main objects are to facilitate such operations, to obtain accurate results, and 20 generally to simplify and improve the construction and operation of machines of this class.

It consists in the construction, arrangement and combination of parts as hereinbelow particularly described and pointed out in the claims.

In the accompanying drawing like characters designate the same parts in the several figures.

Figure 1 is a plan view, parts being broken away, of a computing machine embodying the invention; Fig. 2 is a side elevation of the same as viewed from the right relative to Fig. 1; Fig. 3 is a longitudinal section on the line 3—3, Fig. 1; Fig. 4 is a cross section on the line 4—4, Figs. 1 and 3; and Fig. 5 is a cross section on the line 5—5, Fig. 2.

The machine as shown, comprises a casing 1, which may be made of sheet metal in separable sections detachably connected in any suitable manner to provide for assembling the component parts of the internal mechanism and for convenient access 45 thereto.

The top of the casing adjacent the front end which serves as a key board or plate 2, is formed with a number, in the present case six, parallel key slots 3, running lengthwise thereof. The plate 2 is also preferably formed with a transverse row of eight openings 4, one at the right of each slot. The casing is provided on the top between its rear end and the key slots 3, with a raised wheel housing or hood 6, formed in the upper part of its front wall with a trans-

verse row of parallel vertical slots 7, and below the slots with a transverse row of sight openings 8. Number wheels 10, are rotatably mounted coaxial with one another, 60 on a transverse shaft 11, fastened at the ends to the sides of the casing or hood 6. Each number wheel is provided on its periphery with a series of evenly spaced numbers, zero to nine, which are exposed one 65 at a time through the sight openings 8. Each wheel is also provided on the right hand side with two concentric series of ratchet pins or teeth 12 and 13, each series consisting of ten pins or teeth spaced to 70 correspond with the spacing of the numbers on the periphery of the wheel. Each wheel except the last at the left, is also provided on the opposite or left hand side, with a single carry pin or tooth 14.

Spring pressed dogs or pawls 15, by yielding engagement with the pins or teeth 13, prevent backward rotation and overrunning of the number wheels. These dogs or pawls may be pivoted as shown in Fig. 3, to 80 brackets 16, which are mounted on a board or plate 17, fastened to and supported horizontally in the casing.

At the right of each number wheel 10, a pinion 18 is loosely mounted on the shaft 85 11. A spring pressed pawl 19, Fig. 3 pivoted to each pinion or the hub thereof, is adapted by engagement with the pins or teeth 12, to turn the next number wheel to the left clockwise when the pinion is rotated in that direction.

The pins 12 and 13, with which the pawl 19 and dog 15 of each number wheel engage, may be extended radially and merge with one another and thus form a single 95 series of ten teeth, the two series of pins being the equivalent of a single series of radial teeth.

A number of parallel longitudinally movable key bars 20, are mounted and guided 100 on cross bars or supports 21 and 22, in the upper part of the casing just below the key board or plate 2, there being one of these bars for each number wheel 10 and pinion 18. Each key bar is provided with a rack 105 23, which meshes with the pinion 18 of the corresponding number wheel.

The key bars are provided on the under side at corresponding points between their ends, with depending pins or projections 24, 110 and on the upper side with plates 25, each numbered from zero to nine to correspond

with the numbers of the wheels 10. These numbers are exposed to view one at a time through the eight openings 4 in the key board or plate 2.

5 Each bar 20 is provided with a longitudinal series of nine depressible keys 27, designated by numbers thereon in the order of the corresponding numbers on the bar itself.

10 The keys, which are regularly spaced to correspond with the spacing of the numbers on the wheels 10 and bars 20, are provided with stems 28, passing through the slots 3 in the key plate 2, and guided in the bars, 15 below which they are adapted to project when the keys are depressed. The stems are formed with corresponding elongated notches in one side and are yieldingly held in place in the key bars by a friction brake 20 or drag consisting of spring wires 30, embracing the stems and bent inwardly towards each other and fastened to the key bars between the stems by staples 31, as shown in Fig. 1. One of each pair of wires 30 engaging the flat faces of the notches, holds the stems 28 with the keys 27 from turning, and by engagement with the shoulders at the ends of the notches, limits the vertical movement of the keys.

30 The cross bar 22 serves as a stop for limiting the forward movement of the key bars 20, according to the adjustment of the keys 27, by engagement with the stems 28 of such keys as are depressed.

35 For operating the key bars and turning the number wheels according to the adjustment or setting of the keys, the machine is provided with a transverse shifter bar 34, fastened at the ends to slides 35, which are guided and movable in the casing parallel with the key bars.

40 A rocker shaft 37, supported by bearings on the mounting plate 17 adjacent the rear end of the casing and projecting through 45 openings in the sides thereof, is provided at the ends with arms 38 and 39, connected by links 40 with the slides 35 of the shifter bar 34 through slots 41 in the sides of the casing.

45 The arm 38 is extended and provided with an operating handle 42.

50 For returning the keys 27 to normal position after they have been depressed and have arrested the forward movement of the key bars by engagement with the stop bar 22, the 55 machine is provided with a vertically movable lifter bar 44, having upwardly projecting pins 45, which are guided in the mounting plate 17 in register with the stems 28 of keys which have been depressed and arrested in their forward movement with the bars 60 20 by the stop bar 22.

55 The bar 44 is pivotally connected with levers 46, which are fulcrumed between their ends on brackets 47 attached to the under 65 side of the plate 17. At the ends opposite

the bar 44 the levers 46 are connected by a cross rod 48 which projects at its ends through slots 49 in the sides of the casing 1, into the path of the arms 38 and 39.

60 A spring 50, fastened to the plate 17 and 70 engaging the rod 48, normally holds the lifter bar 44 with its pins 45 in its normal lower position, as shown in Figs. 3, 4 and 5.

75 To turn a number wheel of a higher denomination one step whenever a number wheel of the next lower denomination has been turned one complete revolution, or ten steps, for carrying in the operation of addition, the machine is provided with ratchet bars 52, projecting at their front ends through and guided in the slots 7 of the wheel hood 6, and provided with handles or finger pieces 53. The bars 52 are pivotally connected at their rear ends with rocker arms 54, extending upwardly from a cross 80 shaft or rod 55 on which they are loosely mounted, the shaft or rod 55 being fastened at the ends to the side walls of the hood 6 and supported thereby behind the number 85 wheels 10 parallel with the shaft 11. A ratchet bar is associated with each number wheel 10 at the right hand side thereof, and is guided by its rocker arm 54 and the slot 7 in the hood 6, in position to cooperate 90 with the pins or teeth 13 of the ratchet wheel.

95 Each rocker arm 54, except that at the extreme right, is connected with a wiper arm 56, which extends normally forward from the shaft or rod 55 into the path of the 100 pin or tooth 14 on the left hand side of the number wheel of the next lower denomination, as shown in Figs. 1 and 3.

105 As shown in Fig. 1, the key board or plate 2 is provided at the left hand side of each key slot 3 with a series of numbers, 1 to 9, arranged in reverse order to the numbers 110 designating the keys and opposite the keys in their normal positions. Each of these series or columns of numbers is designated 115 at the top "Sub." They are used in the manipulation of the keys for subtraction.

120 In place of a separate series or column of numbers for each row or series of keys, the key board or plate may be provided with a single series or column of numbers at each or either side, to designate the keys for the operations of subtraction, and instead of numbering the keys themselves for the operations of addition, they may be designated 125 by one or more series or columns of numbers placed in the same order on the key board or plate adjacent one or more of the key slots 3 and opposite the keys in their normal positions.

130 In the operation of the machine for adding, as for example, 8 and 9, all the number wheels and key bars being set at zero, and other movable parts of the machine being 135 in their normal positions as shown in Fig. 2,

the operator first depresses the key marked 8 in the units column, or first column at the right. He then grasps the handle 42 and pulls it forward or towards him as far as 5 it will go. The shifter bar 34 is thus carried forward, and engaging with the lower end of the stem 28 of units key 8, carries it with the units key bar 20, forward, till it engages the stop bar 22, thereby arresting 10 the key bar with the stem of the depressed key in vertical alignment with the right hand lifter pin 45, which is then directly below it, as shown in Figs. 3 and 4. After the movement of the key bar with the depressed key has been thus arrested, a slight continued movement of the handle 42, which movement is then almost directly downward and at right angles to the movement of the key bars, carries the arms 38 and 39 15 downward in engagement with the cross rod 48, thereby raising the lifter bar 44 with the pins 45 and returning the depressed key to its normal position. With the forward movement of the units key bar 20, the units 20 number wheel 10 was turned by the associated rack 23, pinion 18 and pawl 19, in engagement with one of the pins or teeth 12, eight steps, thereby bringing the number 8 thereon, into view through the right hand 25 sight opening 8. The handle 42 is then turned upward and backward to its original position, as shown in Figs. 2 and 5. The shifter bar 34 is thus carried backward to its original position indicated by dotted 30 lines in Fig. 3, and by engagement with the pin or projection 24, returns the units key bar to its normal position, without effect however, on the units number wheel, which is held against backward rotation by the 35 dog 15, the pawl 19 slipping over the ratchet pins or teeth 12 and leaving the number 8 on the units wheel exposed to view.

The operator then proceeds in like manner to register the next number 9, by depressing the key marked 9 in the units column and then pulling the handle 42 towards him, thereby turning the units wheel 10 nine additional steps, and bringing into view 40 through the right hand sight opening 8, the number 7, as shown in Fig. 4. In this operation, the units wheel having been turned altogether more than ten steps, the pin or tooth 14 thereon is carried by the adjacent wiper arm 56, and through the connected 45 rocker arm 54, thrusts the associated tens ratchet bar 52 forward or towards the operator, as shown in Fig. 3. The depressed units key 9 is lifted to its normal position, and the handle 42 being returned by the operator to its original position, again restores the units key bar to its normal position. The tens ratchet bar 52, or the second one 50 from the right, is then pushed back by the operator into its normal position in the hood 6, thereby turning the tens number

wheel one step and bringing the number 1 thereon into view, as shown in Fig. 5, and registering the sum of the two numbers 8 and 9, viz: 17.

To add larger numbers of two or more figures each, as for example, 2738 and 1349, the first number is set up by depressing the keys marked "2", "7", "3" and "8" in the thousands, hundreds, tens and units columns or series of keys respectively. The handle 42 is then pulled over towards the operator, and the shifter bar 34 picks up the stems 28 of the depressed keys in their different positions and carries them forward against the stop bar 22 into transverse alignment with one another and into vertical alignment with the lifter pins 45. The key bars 20 with which the depressed keys are connected, being shifted therewith distances corresponding with the initial positions of the depressed keys relative to the stop bar 22, the numbers 2, 7, 3 and 8 on the several bars from left to right, are brought into view through the corresponding sight openings 4. The number wheels 45 associated with the shifted key bars are also turned correspondingly and bring the numbers 2, 7, 3 and 8 thereon into view through the sight openings 8. The first number to be added is thus displayed in two 50 places and may be easily verified by the operator.

The lifter bar 44 being raised as the handle 42 is carried to the end of its forward movement towards the operator, returns all the depressed keys simultaneously 55 to their normal positions on the bars 20.

The handle 42 is turned backward to its original position and restores all the displaced key bars 20 to normal position, bringing the zeros thereon back into view in the sight openings 4, but leaving the number 2738 displayed in the sight openings 8.

The second number, 1349, is then set up 60 in like manner and registered by depressing the proper keys 27 and moving the handle 42 forward and backward as hereinbefore explained.

In registering the last number, the tens and thousands ratchet bars 52 are pushed 65 forward towards the operator by the carrying mechanism as hereinbefore explained, and the number 3077 will appear in the sight openings 8.

These ratchet bars are then thrust backward by the operator into their original positions, proceeding from right to left, thereby turning the tens and thousands number wheels forward one step each, and displaying in the sight openings 8, the number 70 4087, which is the sum of 2738 and 1349.

Any two or more numbers of denominations and amount within the compass of the machine, may be added in like manner, the machine shown having six number wheels,

being adapted for addition of any numbers whose sum does not exceed 999,999. The number of wheels 10 and parts cooperating therewith may be increased for computations involving larger amounts.

For subtraction the machine is operated in a similar manner. To subtract 1349 from 2738 for example, the larger number or minuend, is set up and registered as already explained. The smaller number or subtrahend is then deducted from the larger number and the result is registered by depressing keys 27 according to the numbers in the columns designated "Sub" at the left of the several rows or series of keys, the subtrahend numeral of each higher denomination being increased by 1 when the minuend numeral of the next lower denomination is less than the numeral of the same denomination in the subtrahend; thus: the units key numbered 1 opposite the numeral 9 in the "Sub" column at the left, the tens key numbered 5 opposite the numeral 5 in the next "Sub" column to the left, the hundreds key numbered 6 opposite the numeral 4 in the next "Sub" column to the left, and the thousands key numbered 9 opposite the numeral 1 in the next "Sub" column to the left are depressed, and the handle 42 is turned forward and backward as in addition, except that the hundreds and thousands ratchet bars which have been shifted forward by the carrying mechanism are not returned by the operator to their original positions so as to turn the corresponding number wheels each one step, as in the operation of addition.

The forward movement of the handle 42 which turns the number wheels in this case brings the numbers 1, 3, 8 and 9 thereon into view in the sight openings 8, and the number 1389 thus displayed is the difference or remainder resulting from the subtraction.

The ratchet bars 52 which have been shifted forward in the operation of the machine for subtraction, may be returned to normal position without turning the number wheels, by lifting them out of engagement with the ratchet pins or teeth 13 and then thrusting them backward into normal position.

The foregoing operations of the machine in subtracting 1349 from 2738 are equivalent to the operations in addition proceeding from right to left:

$$\begin{aligned} 8+1 &= 9 \\ 3+5 &= 8 \\ 7+6 &= (1) 3 \\ 2+9 &= (1) 1, \end{aligned}$$

the carried over numbers in the last two columns to the left, represented above by (1) not being registered.

The machine may be cleared or the number wheels all set at zero, by turning the wheels separately with the ratchet bars 52,

or all the wheels may be turned simultaneously to zero by the key bars 20 and shifter bar 34 operated by the handle 42, keys 27 being depressed to add such a number to that exposed on each wheel through its sight opening 8 as will make 10 and turn the wheel to zero.

Various changes in structural details of the machine may be made without materially affecting its mode of operation and without departing from the principle and scope of the invention as defined in the following claims.

I claim:

1. In a computing machine the combination of a series of number wheels, longitudinally and independently movable parallel key bars each provided with a series of independently depressible keys and with a fixed projection, a fixed stop arranged to engage depressed keys and arrest the movement of the bars in one direction, a manually operated transverse shifting bar adapted by engagement with depressed keys to carry them with their bars in one direction against said stop and by engagement with said fixed projections to return the bars to their normal positions, and means for converting longitudinal movements of the key bars in one direction into corresponding rotary movements of the associated number wheels.

2. In a computing machine the combination of a casing having a key plate with parallel slots and a raised wheel hood with sight openings adjacent one end of the key plate, a series of number wheels mounted in the hood and each numbered from zero to nine, the numbers on each wheel being exposed one at a time through a sight opening in the hood, longitudinally movable parallel key bars mounted in the casing and each provided with a fixed projection and with a series of depressible keys numbered from one to nine, a fixed stop adapted by engagement with depressed keys to arrest the forward movement of the key bars at a certain point, a transverse shifting bar guided in the casing parallel with the key bars and adapted by engagement with depressed keys to shift them forward against the stop different distances according to their positions relative to the bars by which they are carried and by engagement with said projections to return the bars to their normal positions, and means for converting shifting movements of the bars into corresponding rotary movements of the several associated number wheels.

3. In a computing machine the combination of a casing provided with a key plate having parallel longitudinal slots and sight openings adjacent the slots and with a wheel hood having sight openings, wheels mounted in the hood and each having a series of num-

- bers from zero to nine exposed one at a time through an opening in the hood, longitudinally movable parallel key bars mounted in the casing and each having a projection and 5 a series of numbers from zero to nine exposed one at a time through a sight opening in the casing, a corresponding series of depressible keys carried by each key bar, a fixed stop adapted by engagement with depressed keys to arrest the forward movement 10 of the key bars at a certain point, a transverse shifting bar guided in the casing parallel with the key bars and adapted by engagement with depressed keys to shift them 15 forward against the stop and by engagement with said projections to return the bars to normal position, means for converting movements of the bars in one direction into corresponding rotary movements of the wheels, 20 a lifter arranged to raise depressed keys to their normal positions at the limit of their forward movement with the bars, and means for manually operating the shifting bar and lifter.
- 25 4. In a computing machine the combination of a series of number wheels, longitudinally and independently movable parallel key bars each provided with a series of independently depressible keys and with a fixed 30 projection, a fixed stop arranged to engage depressed keys and to arrest the movement of the bars in one direction, a shifting bar disposed transversely to and movable lengthwise of the key bars and adapted by engagement with depressed keys to carry them with 35 their bars in one direction against said stop and by engagement with said fixed projections to return the bars to their normal positions, and a vertically movable lifter 40 adapted to raise the depressed keys to their normal positions at the limit of their movement with the bars determined by the stop.
5. In a computing machine the combination of a series of number wheels each provided 45 with a series of numbers and with a like number of correspondingly spaced ratchet teeth, each number wheel except that of the highest denomination having a carrying tooth, a rocker arm associated with each 50 number wheel, a ratchet bar connected with each rocker arm and operable manually to turn the associated number wheel by engagement with its ratchet teeth, a wiper arm connected with the rocker arm of each number 55 wheel except the units wheel and extending normally into the path of the carrying tooth of the number wheel of the next lower denomination, a series of movable keys for each number wheel, and mechanism controlled in
- operation by the keys and adapted to impart 60 variable rotary movements to the number wheels according to the adjustment of the keys.
6. In a computing machine the combination of a series of number wheels each having a series of numbers from zero to nine exposed to view one at a time, a corresponding series of parallel longitudinally and independently movable key bars, mechanism for imparting rotary movement to each 65 wheel by the movement of the corresponding key bar, a series of depressible keys carried by each bar and having notched stems guided in the bar, and a friction drag for resisting and limiting the movement of the key 70 stems in each bar consisting of spring wires embracing the stems at the notches therein and bent towards each other and fastened to the bar between the stems.
7. In a computing machine the combination 75 of a casing having parallel longitudinal slots in the top and sides, a series of number wheels mounted coaxially in the casing and each having a series of numbers from zero to nine exposed one at a time to 80 view through a sight opening in the casing, a corresponding series of parallel longitudinally movable key bars guided in the casing and each provided with a depending projection, a series of depressible keys carried by 85 each bar and having stems guided therein, a fixed stop bar located below and transversely to the key bars and adapted by engagement with the stems of depressed keys to limit the forward movement of the bars at a 90 certain point, a vertically movable lifter bar provided with upwardly projecting pins registering with the stems of keys in the position in which they are arrested by the stop 95 bar, parallel levers fulcrumed between their 100 ends and connected at one end with the lifter bar, a transverse shifter bar guided and movable lengthwise of and below the key bars and adapted in its forward movement to engage the stems of depressed keys and 105 shift them against the stop bar and in its backward movement to engage said depending projections and return the key bars to normal position, and a transverse rocker shaft provided with arms connected by links 110 with the shifter bar and adapted by engagement with the lifter levers to raise the lifter bar and return depressed keys to normal position.

In witness whereof I hereto affix my signature.

THOMAS J. WAVRUNEK.
